CLAIM

The ornamental design for a stainless steel bottle for liquids, as shown and described.

DESCRIPTION

1. Stainless steel bottle for liquids

1.1 : Perspective

1.2 : Perspective

1.3 : Front

1.4 : Back

1.5 : Top

1.6 : Bottom

1.7 : Left

1.8 : Right

Stainless steel bottle for storing and transporting liquids has a cylindrical shape and includes a tubular neck; concentric grooves on the tubular neck visually divide the tubular neck into strips.
